UNITED STATES PATENT OFFICE.

ESTOL SENN RUSH, OF LOS ANGELES, CALIFORNIA.

TIMER.

Application filed October 27, 1920. Serial No. 419,898.

To all whom it may concern:

Be it known that I, ESTOL SENN RUSH, a citizen of the United States, residing at Los Angeles, county of Los Angeles, and 5 State of California, have invented a new and useful Improvement in Timers, of which the following is a specification.

My invention relates to timers which are especially adapted for use on Model T Ford 10 cars. These timers are used for the purpose of making contact on the low tension side of an ignition system.

In the standard form of timer, a roller is forced outwardly against an annular 15 track consisting of alternating sections of conducting and insulating material.

The principal object of my invention is to construct a timer of this character which will have certain advantages over the prior 20 art.

The invention resides in the novel combination and association of parts illustrated in the drawing set forth in the following specification.

25 In the drawing which is for illustrative purpose only,

Fig. 1 is a perspective view of the timer with a portion of the casing cut away.

Fig. 2 is a perspective view of rotating 30 element of the timer, a portion of the roller being shown in section to better illustrate the invention.

Fig. 3 is a perspective view of the various elements used in Fig. 2, these elements being shown in their disassociated position.

Fig. 4 is a section through the member shown in Fig. 2, and,

Fig. 5 is an axial section through the roller.

40 In the form of my invention shown, a metal casing 11 is provided having a track therein, formed of alternate insulating sections 12 and conducting sections 13. The conducting sections 13 are insulated 45 from each other and from the casing 11 and are each provided with a binding post 14 to which wiring may be connected in accordance with standard practice. The members 11 to 14 are at the present time standard in the well known Model T Ford automobile forming no portion of my invention.

My invention resides in the rotating member shown in Fig. 2, this member consists of a hub 21 adapted to fit upon the cam 50 shaft of the Ford engine and having a key way 22 in which a pin 23 may be seated,

this pin being retained by a retaining cap 24. Formed on the hub 21 is a boss 25 and a bearing 26 having a bore 27 and a slot 28. Fitting in the bore 27 is one arm 31 of a so swinging member 32, this member also having a spindle 33 with a key way 34 cut therein. The arm 31 has a hole 35 into which one end 36 of a spring lever 37 fits, the spring lever 37 fitting in the slot 28 and 35 extending outwardly as shown in Fig. 4 and having a spring seat 38 formed thereon. A compression spring 39 seats on the boss 25 and on the seat 38 tending to rotate the swinging arm 32 in a clockwise direction 70 about the arm 31 as viewed in Fig. 4. Turning freely on the spindle 33 is a roller 41, this roller having an annular cavity 42 in one end thereof in which a cup washer 43 is seated. This cup washer is provided with 75 a key 44 fitting in the key way 33. A conical spiral spring 45 is seated in the cup washer 43, being also seated against a washer 46 held in place by a pin 47 on the spindle 32. The roller 41 is provided with 80 a conical flange 51.

The method of operation of my invention is as follows:

The parts being assembled as shown in Fig. 1, the roller 41 is forced outwardly 85 against the track formed of the members 12 and 13 by means of the spring 39, thus making a positive contact between the cylindrical periphery of the roller 41 and the inner surface of the track. In the same 90 time, the roller 41 is forced axially on the spindle 33 by the spring 45 thus holding the flange 51 in contact with the side of the track formed of the members 12 and 13, this track being slightly beveled or coned 95 to suit the contour of the flange 51. The washer 43 is prevented from turning by the key 44 and this washer is forced over by the spring 45. A dual contact is, therefore, made between the roller 41 and the 100 track formed of the members 12 and 13, the spring 39 maintaining one of these contacts and the spring 45 maintaining the other. The spring tensions are so balanced that a uniform wear takes place on both of these 105 surfaces, the washer 43 being prevented from rotation acts as a brake on the roller 41 and results in a slight slippage on the track so there is a slight wear or rubbing action tending to keep the surfaces clean. 110 The washer 43 and the spring 45 also serve to conduct the current from the washer 43

to the swinging member 32 thus preventing arcing or wear in the bore of the roller 41.

I have found by careful tests over a long period that by using a dual contact, 5 the destructive arcing found in other forms of timers is very greatly reduced. There is, of course, an arc whenever the roller leaves one of the conducting members 13 and this arc cannot be prevented. In the ordinary 10 form of timer, however, there is a great deal of additional arcing due to the roller breaking contact prematurely with the conducting members 13 and in my invention this is entirely prevented. By eliminating this 15 arcing, I also improve the timing and general performance of the engine to which the timer is attached.

I claim as my invention:

1. In a timer having a track formed of 20 alternate sections of conducting and insulating material; the combination of a hub fitting over a cam shaft at the axis of said track; means for securing said hub to said cam shaft; a bearing extending outwardly 25 from said cam shaft and having a bore; a swinging member having two parallel arms, one of which fits in said bore and the other of which forms a spindle; a spring lever secured at one end to said swinging member 30 so that it turns therewith about the axis of said bore; a spring tending to turn said swinging member about the axis of said bore; and a roller turning on said spindle.

2. In a timer having a track formed of 35 alternate sections of conducting and insulating material; the combination of a hub fitting over a cam shaft at the axis of said track; means for securing said hub to said cam shaft; a bearing extending outwardly 40 from said cam shaft and having a bore and a slot cutting across said bore at right angles to said bore; a swinging member pivoted in said bore and carrying a spindle parallel to said cam shaft; a spring lever fitting in said slot and engaging said swinging member; a boss on the exterior of said hub; a compression spring between the free 45 end of spring lever and said boss; a flanged roller turning and sliding on said spindle; a spring on said spindle forcing said roller to slide axially on said spindle; a cup washer fitting inside 50 a cavity in said roller and forming a seat for one end of said spring; and means for preventing said cup washer from turning 55 on said spindle.

3. In a timer having a track formed of 60 alternate sections of conducting and insulating material; the combination of a hub fitting over a cam shaft at the axis of said track; means for securing said hub to said cam shaft; a bearing extending outwardly 65 from said cam shaft and having a bore and a slot cutting across said bore at right angles to said bore; a swinging member pivoted in said bore and carrying a spindle par-

allel to said cam shaft; a spring lever fitting in said slot and engaging said swinging member; a boss on the exterior of said hub; a compression spring between the free end of spring lever and said boss; a flanged 70 roller turning and sliding on said spindle; and a spring tending to move said roller axially on said spindle.

4. In a timer having a track formed of alternate sections of conducting and insulating material; the combination of a hub fitting over a cam shaft at the axis of said track; means for securing said hub to said cam shaft; a bearing extending outwardly 75 from said cam shaft and having a bore and a slot cutting across said bore at right angles to said bore; a swinging member pivoted in said bore and carrying a spindle parallel to said cam shaft; a spring lever fitting in said slot and engaging said swinging member; a boss on the exterior of said hub; a compression spring between the free end of spring lever and said boss; and a 80 roller turning on said spindle.

5. In a timer having a track formed of 85 alternate sections of conducting and insulating material; the combination of a hub fitting over a cam shaft at the axis of said track; means for securing said hub to said cam shaft; a bearing extending outwardly 90 from said cam shaft and having a bore; a swinging member pivoted in said bore and carrying a spindle parallel to said cam shaft; a spring lever secured at one end to said swinging member so that it turns there- 95 with about the axis of said bore; a boss on the exterior of said hub; a compression spring between the free end of spring lever and said boss; a flanged roller turning and sliding on said spindle; a spring on said 100 spindle forcing said roller to slide axially on said spindle; a cup washer fitting inside a cavity in said roller and forming a seat for one end of said spring; and means for preventing said cup washer from turning 105 on said spindle.

6. In a timer having a track formed of alternate sections of conducting and insulating material; the combination of a hub fitting over a cam shaft at the axis of said 115 track; means for securing said hub to said cam shaft; a bearing extending outwardly from said cam shaft and having a bore; a swinging member pivoted in said bore and carrying a spindle parallel to said cam 120 shaft; a spring lever secured at one end to said swinging member so that it turns there- with about the axis of said bore; a boss on the exterior of said hub; a compression 125 spring between the free end of spring lever and said boss; a flanged roller turning and sliding on said spindle; and a spring tending to move said roller axially on said spindle.

7. In a timer having a track formed of 130

alternate sections of conducting and insulating material; the combination of a hub fitting over a cam shaft at the axis of said track; means for securing said hub to said cam shaft; a bearing extending outwardly from said cam shaft and having a bore; a swinging member pivoted in said bore and carrying a spindle parallel to said cam shaft; a spring lever secured at one end to

5 said swinging member so that it turns there-

10

with about the axis of said bore; a boss on the exterior of said hub; a compression spring between the free end of spring lever and said boss; and a roller turning on said spindle.

15

In testimony whereof, I have hereunto set my hand at Los Angeles, California, this 22nd day of October, 1920.

ESTOL SENN RUSH.
